CLAIM

The ornamental design for a track bolt, as shown and described.

DESCRIPTION

FIG. 1 is a front view of the design;

FIG. 2 is a left view of the design;

FIG. 3 is a right view of the design;

FIG. 4 is a bottom view of the design;

FIG. 5 is an isometric view of the design;

FIG. 6 is a rear view of the design; and,

FIG. 7 is a top view of the design.

The broken lines in the drawings illustrate portions of the track bolt and form no part of the claimed design.
